UNITED STATES PATENT OFFICE.

SIDNEY D. WALDON, OF DETROIT, MICHIGAN, ASSIGNOR TO PACKARD MOTOR CAR COMPANY, OF DETROIT, MICHIGAN, A CORPORATION OF MICHIGAN.

MUFFLER.

1,094,105.

Specification of Letters Patent. Patented Apr. 21, 1914.

Application filed March 16, 1911. Serial No. 614,929.

To all whom it may concern:

Be it known that I, SIDNEY D. WALDON, a citizen of the United States, and resident of Detroit, Wayne county, State of Michigan, have invented certain new and useful Improvements in Mufflers, of which the following is a specification.

This invention relates to mufflers and particularly to mufflers for use with multi-cylinder internal combustion engines.

An object of the invention is to make a muffler of simple and inexpensive construction, one that is easy to assemble and to repair and one that will cushion the gases and cause them to be broken up and finally expelled in a more or less steady stream, at the same time with little or no back pressure.

Other objects will appear from the following specification taken in connection with the drawings, in which,

Figure 1 is a longitudinal section through a muffler embodying the invention, and Fig. 2 is a cross section on the line 2—2 of Fig. 1.

Referring to the drawings, it will be seen that the muffler consists of an outer cylindrical casing 10 which is preferably lined with asbestos as shown at 11, an outer tubular member 12 concentrically arranged within

the casing, an inner tubular member 13 concentrically arranged within the first or tubular member 12, and end plates 14 and 15 which close the ends of the tubular members of the casing excepting the forward end of the inner tubular member 13 which projects through the end plate 14 and is provided with a coupling member 16 by

which it may be attached to the motor exhaust pipe. The end plates 14 and 15 are secured to the tubular members and the casing by the stay rods 17, three of these rods being shown in the drawings, and these rods are preferably arranged longitudinally in the annular space 18 between the outer tubular member 12 and the casing 10.

The inner tubular member 13 is provided adjacent its forward or inlet end with several series of perforations 19 through which the exhaust gases escape from the cylindrical member 13 into the outer cylindrical member 12. From here the gases pass through several series of perforations 20 in the rearward end of the outer tubular mem-

ber 12, thus being further broken up and passed into the annular space between the outer tubular member 12 and the casing 10.

The outer tubular member 12 is preferably bent inwardly along one of its sides as shown in the drawing for the purpose of slightly enlarging the annular space 18 at this point to accommodate the outlet tube 21 which may extend throughout a portion of the length of the muffler and inside of the casing 10. This outlet tube 21 passes through a suitable opening in the end plate 15 and may be provided with an extension 22 extending rearwardly therefrom for the purpose of discharging the gases at a suitable point.

It will be understood that the gases passing from the motor exhaust pipe into the inner tubular member 13 will be cushioned by the air or other gas in the member between the perforations 19 and the rearward end thereof, and the gases will then take a circuitous passage through the opening 19, rearwardly through the member 12 and out through the openings 20, thence forwardly again through the annular space 18 between the member 12 and the casing 10 and finally passing outward through the outlet pipe 21 and its extension 22.

It will also be understood that the inner member 13 may be removed by taking out the bolts 23 in the forward end thereof and the bolt 24 in the rear, without dismantling the remainder of the muffler. Also the entire muffler may be dismantled by removing the three rods 17 and bolt 24, and as easily reassembled.

Having thus described my invention, what I claim is:

1. A muffler comprising a plurality of concentrically arranged cylindrical elements, end plates therefor, and an outlet pipe extending through one of the end plates and into the space between said cylindrical elements, the inner of said cylindrical elements having an inwardly bent portion, substantially as shown and described.

2. A muffler comprising an outer cylindrical casing, an outlet connection in said casing, concentric outer and inner tubular members therein, an exhaust pipe connection at one end of said inner tubular member, said inner tubular member being per-

forated adjacent said exhaust pipe connection end only, said tubular outer member being perforated adjacent the opposite end only, end plates abutting against the ends of
5 said elements and said casing and rods connecting the end plates and passing between said elements.

In testimony whereof I affix my signature in the presence of two witnesses.

SIDNEY D. WALDON.
